UNITED STATES PATENT OFFICE.

IRVING SMITH, OF WINSTED, CONNECTICUT.

SAFETY RAZOR.

Application filed March 31, 1925. Serial No. 19,583.

To all whom it may concern:

Be it known that I, IRVING SMITH, a citizen of the United States, and a resident of Winsted, county of Litchfield, and State of Connecticut, have invented certain new and useful Improvements in Safety Razors, of which the following is a specification.

This invention relates to razors, and more particularly to a safety razor having a thin flat handle arranged obliquely to the edge of the blade so that the correct diagonal shaving stroke will be easily obtained by the user.

The object of this invention is to provide a device of the above nature which will be simple in construction, inexpensive to manufacture, easy to manipulate, ornamental in appearance, and very efficient and durable in use.

With these and other objects in view there have been illustrated on the accompanying drawings, several forms in which the invention may be conveniently embodied in practice.

Fig. 1 represents an end view of the first form of safety razor embodying the invention.

Fig. 2 is a side sectional view of the same, taken along the line 2—2 of Fig. 1, looking in the direction of the arrows.

Fig. 3 is a top sectional view of the same, taken along the line 3—3 of Fig. 2 looking in the direction of the arrows.

Fig. 4 is a cross-sectional view of the handle of the safety razor, taken along the line 4—4 of Fig. 2.

Fig. 5 is an end view of a modified second form of the invention.

Fig. 6 is a side sectional view of the same, taken along the line 6—6 of Fig. 5, looking in the direction of the arrows.

Fig. 7 is a top view of the second form of safety razor.

Fig. 8 is a perspective view of the clamping plate employed with the second form of the invention.

Fig. 9 is a perspective view of the lower portion of the handle of the second form of the invention.

Fig. 10 is a side view, partly in section, of the lower part of a modified third form of the invention.

Figs. 11 and 12 are top and end views respectively of one form of razor blade adapt-

ed to be used with either of the three above-illustrated forms of safety razor.

Figs. 13 and 14 are top views of two modified forms of razor blade.

Fig. 15 is a top view of a modified form of guard member adapted for use with any of the above-illustrated forms of safety razor.

Fig. 16 is a side sectional view of the same, taken along the line 16—16 of Fig. 15.

Fig. 17 is a top view of another modified form of guard member.

Figs. 18 and 19 are top and end views respectively of a modified form of clamping plate to be used with the guard member shown in Figs. 15 and 16.

Referring now to the drawings in which like reference numerals denote corresponding parts throughout the several views, the numeral 20, Figs. 1 and 2, indicates a clamping plate for a razor blade 27, said clamping plate and razor blade being in the form of oblique parallelograms. The clamping plate has curved upper and lower faces, and is provided with a pair of end pins 21 and 22 and a central upstanding tapped post 23.

The post 23 has an enlarged base section 24 with parallel flat side faces, and above said base section 24 the post 23 has a reduced section with flat side faces 25 and 26, said faces being parallel to the ends of the clamping plate 20.

The razor blade 27 has a pair of end apertures adapted to fit over the pins 21 and a central aperture to surround the post 23, said blade being covered by a guard member 28 which has rows of teeth 29 and 30 on its opposite sides. The guard member 28 has the same oblique parallelogram shape as the clamping plate 20 and blade 27 and is held against said blade by means of a screw rod 31 passing through the interior of a handle 32.

The screw rod 31 is provided at its outer end with a knurled knob 33 and has its inner end 34 threaded and adapted to be screwed into the tapped post 23, previously described. The handle 32 is provided with flat parallel opposite side faces 35 and 36, and is non-rotatively held at an oblique angle to the sides of the blade and parallel to the ends of said blade, said angle being such that in shaving, it will be easy for the user to obtain the correct diagonal stroke across

the face. The inner end of the handle 32 is provided with a slot 37 having curved ends and flat sides and adapted to fit over the ends and sides of the post 23.

5 By means of this construction, when the screw rod 31 is screwed into the post 23, the handle member 32 will be forced down upon the guard member 28, which in turn will press the blade 27 upon the clamping plate 20.

10 In Figs. 5 to 9 a modified second form of the invention is illustrated. This form of safety razor comprises a clamping plate 38 having the same oblique parallelogram shape as in the first form, and having end pins 39 and 40 identical with the pins 21 and 22 of the first form. The clamping plate 38 is provided with an upstanding post 41 threaded on its exterior at 42 and 15 having a reduced tongue 43 at its top portion, said tongue having flat sides 44 and 45 parallel to the ends of said clamping plate 38.

20 A guard member 46 and a blade 47, which 25 are identical with the guard member 28 and blade 27 of the first form of razor shown in Figs. 1 to 4, are adapted to be held upon the clamping plate 38 by means of a swivel collar 48, as most clearly shown in Figs. 6 and 9. The swivel collar 48 is preferably 30 knurled on its exterior and has an inwardly directed lug 49 at its top adapted to fit loosely within an annular slot 50 in a flat handle member 51, said handle member 51 35 having flat sides 52 and 53 parallel to the ends of the clamping plate, as in the first illustrated form of the invention.

40 In order to hold the handle rigidly in its correct angular position with respect to the blade, the handle 51 is provided with a slot 54 adapted to fit snugly over the flat tongue 43 of the bed post.

45 A still further modified third form of the invention is shown in Fig. 10. This form of razor is identical with the forms shown in Figs. 5 to 9, except that the bottom of the handle is provided with a flat tongue 55 and the center post of the clamping plate is provided with a slot 56 fitting over said tongue 55 for holding the handle 50 55 at the correct oblique position.

55 In Figs. 11 to 14, three modified forms of razor blade are illustrated. In each form, the blade is in the shape of an oblique parallelogram corresponding to the shape of the clamping plate as shown in Figs. 3 and 7.

60 In the form shown in Fig. 11, the blade is provided with a pair of end apertures 58 and 59 for fitting over the end pins of the clamping plates, and said blade has a 65 central aperture 60, the latter having the shape of an oblique parallelogram with its sides parallel to the ends of the blade. The central aperture is adapted to fit snugly

over the center posts of any one of the clamping plates shown.

65 In the form shown in Fig. 13, the blade is provided with a cross shaped hole 61, the ends of which communicate with central 70 side arms 62 and 63 thereof.

75 The form of blade shown in Fig. 14 is identical to that shown in Fig. 11 except that the central post aperture 64 is made in the shape of an ellipse.

80 In Figs. 15 and 16 a modified form of guard member is shown. In this form of guard member, a pair of longitudinal ribs 65 and 66 are struck up from the base of the guard member to provide a pair of 85 grooves to fit over a pair of ribs 67 and 68 extending out from each side of a tapped post 69 which projects up from a clamping plate 70, as clearly shown in Figs. 15, 18, and 19. It will be understood that the modified forms of guard member and clamping plate shown in Figs. 15, 18, and 19 may be employed interchangeably in any 90 of the three illustrated forms of razor.

95 In Fig. 17 a still further modified form of guard member 71 is illustrated. This form of guard member has a cross-shaped hole 72 similar to the hole 61 of the blade shown in Fig. 13.

100 The guard member 71 is especially adapted for use with the clamping plate 70 shown in Fig. 18, but it may also be used with the other illustrated forms of clamping plate within the general spirit and scope of the invention.

105 While there have been disclosed in this specification several forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and 110 embodiments coming within the scope of the following claims.

115 Haviug thus fully described the invention, what is claimed as new, and for which it is desired to secure Letters Patent, is:

120 1. In a safety razor, a clamping plate, a razor blade seated on said clamping plate, a guard member covering said blade, and a flat handle for holding said guard member against said blade, said clamping plate and handle having interengaging means to hold said handle obliquely to the edge of said blade, whereby the correct diagonal shaving stroke may be easily obtained by the user.

125 2. In a safety razor, a clamping plate, a razor blade seated on said clamping plate, a guard member covering said blade, and a flat handle for holding said guard member against said blade, said clamping plate and 130

handle having interengaging means to non-rotatively hold said handle obliquely to the edge of said blade, whereby the correct diagonal shaving stroke may be easily obtained by the user.

3. In a safety razor, a clamping plate for supporting a razor blade, means to cover the edge of said blade and protect the face of the user, a flat handle for said razor, said clamping plate having an upstanding tongue, said handle having a slot adapted to fit non-rotatively over said tongue, and means for detachably connecting said handle to said clamping plate.

4. In a safety razor, a clamping plate for supporting a razor blade, means to cover the edge of said blade and protect the face of the user, a flat handle for said razor, said clamping plate having an upstanding flat tongue, said handle having a slot adapted to fit non-rotatively over said tongue, and means for detachably connecting said handle to said clamping plate.

5. In a safety razor, a clamping plate for supporting a razor blade, means to cover the edge of said blade and protect the face of the user, a flat handle for said razor, said clamping plate having an upstanding tongue, said handle having a slot adapted to fit non-rotatively over said tongue, and means for detachably connecting said handle to said clamping plate, said tongue and slot being positioned obliquely to the edge of said blade whereby the correct diagonal stroke may easily be obtained by the user.

6. In a safety razor, a clamping plate for supporting a razor blade, means to cover the edge of said blade and protect the face of the user, a flat handle for said razor, said clamping plate and handle having interfitting parts adapted to hold said handle against rotation relative to said clamping plate and means for detachably connecting said handle to said clamping plate.

7. In a safety razor, a clamping plate for supporting a razor blade, means to cover the edge of said blade and protect the face of the user, a flat handle for said razor, said clamping plate and handle having interfitting parts adapted to hold said handle against rotation relative to said clamping plate, and means for detachably connecting said handle to said clamping plate, said handle being positioned obliquely to the edge of said blade whereby the correct diagonal shaving stroke may be easily obtained by the user.

8. In a safety razor, a clamping plate for supporting a razor blade, means to cover the edge of said blade and protect the face of the user, a flat handle for said razor, said clamping plate and handle interengaging with each other to hold said handle rigidly against rotation relative to said clamping plate, and a collar member con-

nected to said handle having detachable locking engagement with said clamping plate.

9. In a safety razor, a clamping plate for supporting a razor blade, means to cover the edge of said blade and protect the face of the user, a flat handle for said razor, said clamping plate and handle interengaging with each other to hold said handle rigidly against rotation relative to said clamping plate, and a collar member connected to said handle having detachable locking engagement with said clamping plate, said handle being positioned obliquely to the edge of said blade whereby the correct diagonal shaving stroke may be easily obtained by the user.

10. In a safety razor, a clamping plate for supporting a razor blade, a guard member for covering said plate and adapted to protect the face of the user, said clamping plate having an upstanding threaded post, a flat tongue projecting upwardly from said post and set obliquely to the edge of said blade, a flat handle for said razor, said handle having a slot adapted to fit non-rotatively upon said tongue, said handle being held obliquely to the edge of said blade whereby the correct diagonal shaving stroke may be easily obtained by the user, and a tapped swivel collar mounted on said handle for engaging said threaded post whereby said handle will be detachably locked in operating position upon said post.

11. In a safety razor, a clamping plate having a central obliquely disposed handle-supporting post, a pair of ribs extending longitudinally at either side of said post, a razor blade having a single elongated aperture adapted to seat on said clamping plate and to fit around said post and ribs, means for covering said blade and protecting the face of the user, a flat handle detachably connected to said post and positioned obliquely to the edge of said blade, and means for locking said handle to said post.

12. In a safety razor, a clamping plate having a central obliquely disposed handle-supporting post, a pair of ribs extending longitudinally at either side of said post, a razor blade adapted to seat on said bed plate and to fit around said post and ribs, means for covering said blade and protecting the face of the user, and a flat handle detachably connected to said post and positioned obliquely to the edge of said blade, and means for locking said handle to said post.

13. In a safety razor, a clamping plate having a central obliquely disposed handle-supporting post, a pair of ribs extending longitudinally at either side of said post, a razor blade adapted to seat on said clamping plate and to fit around said post and ribs, a guard member for covering said

blade and protecting the face of the user, said guard member fitting over the ribs of said clamping plate and held in alinement by said ribs, a flat handle detachably connected to said post and positioned obliquely to the edge of said blade, and means for locking said handle to said post.

14. In a safety razor, a clamping plate having a central obliquely disposed handle-

10 supporting post, a pair of ribs extending longitudinally at either side of said post, a razor blade adapted to seat on said clamping plate and to fit around said post and ribs, a guard member for covering said blade

15 and protecting the face of the user, said guard member having a pair of upwardly extending grooves fitting over the ribs of said clamping plate to accurately aline said guard member thereon, a flat handle detach-

20 ably connected to said post and positioned obliquely to the edge of said blade, and means for locking said handle to said post.

15. In a safety razor, a clamping plate for supporting a razor blade, said clamping 25 plate having a central obliquely disposed handle-supporting post, a guard member for covering said razor blade and protecting the face of the user, said clamping plate and guard member having an interfitting rib 30 and groove adapted to accurately aline one with the other, and a flat handle member detachably connected to said post and positioned obliquely to the edge of said blade.

16. In a safety razor, a clamping plate 35 for a razor blade, a guard member for covering said blade and protecting the face of the user, a handle for said razor having an interlocking recess, said clamping plate having a threaded stud to interlock with said recess to prevent relative rotation, and clamping means for engaging the threads of said stud for drawing the parts of the razor together.

17. In a safety razor, a clamping plate for supporting a razor blade, said clamping plate having a central handle-supporting

post, said post having a transversely extending portion, a razor blade having an aperture adapted to fit around said post and transversely extending portion, a guard 50 member for covering said blade, and a handle having a socket fitting over said post and said transversely extending portion, said handle engaging said guard member for holding said blade between said guard 55 member and said clamping plate.

18. In a safety razor, a clamping plate for supporting a razor blade, said clamping plate having a central handle-supporting post, said post having portions extending transversely at either side thereof, a guard member for covering said blade, and a handle having a socket fitting over said post and said transversely extending portions, said handle engaging said guard mem- 60 ber for holding said blade between said guard member and said clamping plate. 65

19. A blade for use in safety razors formed in the shape of an oblique parallelogram, said blade having an obliquely trans- 70 verse slot at its centre shaped to fit over a transversely extending portion of the central post of a razor clamping plate.

20. A blade for use in safety razors formed in the shape of an oblique parallelogram, said blade having a central aperture 75 consisting of a pair of longitudinal slots, and a pair of transverse slots oblique to the longitudinal centre line of said blade.

21. In a safety razor, a clamping plate for a razor blade, said clamping plate having a shank, a guard member for covering said blade and protecting the face of the user, a handle for said razor, said clamping plate shank and handle having longitudinally telescopic non-rotative engagement with each other, and clamping means for drawing the parts of the razor together. 85

In testimony whereof, I have affixed my signature to this specification.

IRVING SMITH.
